CLAIM

The ornamental design for a protective shield for telephone handset, as shown and described.

DESCRIPTION

FIG. 1 is a perspective view of a protective shield for telephone handset showing my new design;

FIG. 2 is a side elevation view thereof;

FIG. 3 is a top plan view thereof;

FIG. 4 is an end elevational view thereof;

FIG. 5 is a elevational view from the opposite end thereof; and

FIG. 6 is a bottom plan view thereof.

Fig. 1.

Fig. 2.

Fig. 4.

Fig. 3.

Fig. 5.

Fig. 6.
